UNITED STATES PATENT OFFICE.

PAUL HANNAGAN, OF LAWRENCE, MASSACHUSETTS.

DUMPING-WAGON.

1,176,677.

Specification of Letters Patent. Patented Mar. 21, 1916.

Application filed May 29, 1912. Serial No. 700,386.

To all whom it may concern:

Be it known that I, PAUL HANNAGAN, a citizen of the United States, residing at Lawrence, in the county of Essex, State of Massachusetts, have invented a certain new and useful Improvement in Dumping-Wagons, of which the following is a specification, reference being had therein to the accompanying drawings.

10 The invention comprises an improved construction of frame providing for hanging the wagon-body low down between the wheels; also, permitting of propulsion by horses or motor, as preferred.

15 It further comprises novel means of raising and lowering a tilting wagon-body.

The invention is illustrated in the drawings in which,—

Figure 1 is a side elevation of a wagon containing one embodiment of the invention. Fig. 2 is a plan thereof with the seat and portion of the front platform and wagon-body broken away. Figs. 3 and 4 are views on the order of side elevations chiefly intended to show the wagon-body in partly-tilted and fully-tilted positions, respectively. Figs. 5 and 6 show in side view and plan a second embodiment of the portion of the invention relating to the means of raising and lowering a wagon-body. Figs. 7 and 8 show another embodiment.

The wagon-frame comprises upper side-bars 1, 1, which preferably are channel-bars, one or more cross-bars joining said side-bars at the front end of the frame and one of which may constitute the front-end cross-bar 2, lower side-bars 3, preferably of channeled form, upright tie-bars 4, 4^a, 4^b, etc., connecting together the upper and lower side-bars at each side of the frame, inclined truss-bars 5, 5^a, also extending from the upper side-bar to the lower one at each side of the frame and the truss-bar 5^a being bolted to upright tie-bar 4^c, a front-end cross-bar 6 between the front ends of the lower side-bars, and cross-bars 7, 7, between the lower side-bars. The upper and lower side-bars are flanged at top and bottom, to secure strength and stiffness with comparative lightness. Preferably, the cross-bars 7, 7, are composed of flat stock having the ends thereof bent up outside the lower side-bars 3, the said cross-bars being placed against the under edges of the lower side-bars 3, and secured in place by bolts or rivets 8, 8, passed through said bent-up ends

and the lower side-bars. At 9 is a cross-bar at the rear of the wagon-frame, extending from one lower side-bar to the other, and having the wagon-body 10 mounted thereon by straps or bearings 9^a connected to the rear portion of the wagon-body and fitted to said cross-bar with capacity to turn thereon. At 11 is a drop-axle, extending across beneath the lower side-bars, and secured by its end-portions to the said lower side-bars. 12, 12, are the rear wheels, they being mounted upon the opposite ends of the said drop-axle. The lower side-bars 3 rest upon the said drop-axle of the said rear wheels, and are supported thereby. The said lower side-bars, combined with the upright tie-bars 4, 4^a, 4^b, etc., and inclined truss-bars 5, 5^a, constitute an inclosing frame for the portion of the wagon-body which hangs down between the upper side-bars and below the latter. The front upright tie-bars 4 are a little in front of the front end of the wagon-body. The upper side-bars 1, 1, project some distance to the front, beyond the front end of the wagon-body and the said depending framework. The upper horizontal portion of the framework therefore projects at the front end of the vehicle, and it may project to any desired length. Beneath the forwardly projecting portion is thereby provided a space within which may be located a truck with wheels and a pole or shafts, etc., for hitching horses, or a self-propelling tractor, or an engine or motor 13 of any approved character can be attached directly to the overhang, thereby permitting the body of the wagon to be located close to the ground in consequence of locating the power mechanism entirely at the front end of the wagon-body instead of underneath the same. In Figs. 1 to 4 the shaft 13^a of said engine or motor carries sprocket-wheels 13^b, 13^b, from which sprocket-chains 13^c, 13^c, pass to sprocket-wheels 13^d, 13^d, on wheels 12, 12, for operating the latter to propel the wagon. The elevation of the overhang, as shown in Figs. 1, 3 and 4, provides also for free turning of the front truck under the body-frame when horses are used. When horses are not used, auto-wheels, as at 14, may be conveniently mounted in connection with the overhang.

For the purpose of tilting the body I provide a carriage, as 15, that is mounted upon the upper side-bars 1, 1, with capacity to travel thereon from the front end of the

wagon toward the rear end, and vice versa. It is shown provided with rolls 16, 16, fitting in the grooves of the said side-bars between the upper and lower flanges, which in this instance are turned outward. The outward facing of the flanges is preferred, but not essential in all cases. I combine this carriage with the wagon-body 10 by means arranged to act to first raise the front end 5 of the said body high enough to permit the carriage, or parts carried thereby, to enter beneath the body or parts in connection therewith, and then cause movement of the carriage toward the rear end of the vehicle, 10 under the body, to further tilt the wagon-body and effect the dumping. The specific means and manner of combining the carriage with the body to secure the described mode of operation and produce the desired 15 results may vary in practice. In Figs. 1 to 4 the carriage is equipped with toothed pinions 17, 17, Fig. 2, the number of which may vary, fixed upon a shaft 18, extending transversely of the carriage and mounted at 20 its ends in bearings in the side-pieces of the carriage, the said toothed pinions meshing with toothed racks 19, 19, attached to the wagon-body. Two of such pinions and a corresponding number of racks are shown 25 herein, but I may in practice employ a single pinion and rack, or more than two. For the purpose of raising the front end of the wagon-body high enough to permit the carriage, or parts in connection therewith, to 30 pass under the wagon-body, or parts in connection with the latter, the said racks 19, 19, are extended vertically upon the front end of the wagon-body as shown. Suitable provision is made in practice for rotating the 35 shaft 18, either by hand or by power, as desired. Herein, for such purpose, the said shaft has fixed upon one end thereof a toothed wheel, 20, with which meshes a carrier or idle toothed wheel, 21, fixed to which 40 is a second toothed wheel, 22, which meshes with a toothed pinion 23 on a shaft 24 having a suitable crank and handle 25. The said toothed wheels 21, 22, 23 and shaft 24 are mounted on carriage 15. The described 45 gearing between the crank and the pinion shaft serves to compound or increase the power. Other convenient mechanical arrangements for rotating the shaft 18 may be employed in practice, such for instance as 50 a worm and worm-gear. As the shaft 18 and pinions 17, 17, are rotated, the front end of the wagon-body is elevated. Suitable provisions are made in practice for preventing the pinions from springing out of mesh 55 with the racks. In the present instance, plates 26, 26, are mounted loosely upon the pinion-shaft at opposite sides of each pinion 17. These plates carry projections, which enter grooves in the sides of the racks, as 60 represented in Fig. 2. Said projections may 65 consist of simple pins or the like, or may carry anti-friction rolls. As the front end of the body is swung upward, the carriage shifts its position upon the supporting side-bars, in consequence of the engagement just 70 described with the grooved sides of the racks, and as soon as the wagon-body has been raised far enough to permit the carriage to enter beneath such end, the carriage is drawn under the elevated lower front 75 corner of the latter, as in Fig. 3. I provide in connection with the carriage means of supporting the pressure as the carriage passes under the body, and during the continued movement of the carriage along under 80 the body toward the rear end of the wagon. The said means preferably comprises disks or rolls 27, 27, mounted upon the carriage. In this instance the said rolls are mounted loosely upon the shaft 18. The number 85 thereof may vary from one to more than two, and the location of such rolls or the substitutes therefor may vary. I do not limit myself to mounting them upon the shaft 18. The continued rotation of the shaft 18 90 causes the carriage to travel toward the rear end of the wagon as a consequence of the engagement of pinions 17, 17, with the portions of the racks 19, 19, which extend along under the bottom of the wagon-body. 95 In doing so it elevates more and more the front end of the wagon-body, tilting the same around the rear cross-bar 9 upon which it is pivoted, as in Fig. 4, until the body has been tilted to the desired position. 100

The body will be prevented from overturning backwardly by reason of the engagement of the projections of the plates 26, 26, in the grooves of the racks, and further, of the engagement of the rolls 16, 16, 105 with the upper flanges of the upper side-bars 1, 1. The weight of the uplifted portion of the wagon-body (Fig. 4) will tend to cause the carriage to travel forward toward the front end of the wagon. The 110 speed of the return may be controlled by means of handle 25, or the return of the carriage may be caused by a reverse turning movement of the shaft 18 and its pinions. The movement of the carriage forward to 115 the front end of the wagon will lower the front end of the wagon-body, and draw it down in case it should not move readily, until the position shown in Fig. 3 is reached, and then, after the carriage has passed in 120 front of the front corner of the body, the continued rotation of shaft 18 will lower the wagon-body or permit the same to lower wholly to its position in Fig. 1 in consequence of the action of the pinions in the 125 upright portions of the racks upon the front of the wagon-body. Thereby the wagon-body is lowered gradually and easily, under full control, to its normal position resting upon its supports in the depending frame. 130

A pawl or dog 29 engages with one of the toothed wheels to lock the body in any position of complete or partial elevation. This locking means enables the body to be used in 5 a partly elevated and inclined position, if desired, and prevents the weight of the uplifted wagon-body from forcing the carriage forward except when desired.

The carriage 15 is shown in Fig. 1 as 10 adapted to pass forwardly partly under a seat 28 for the driver. In other constructions, with a lower body, and with a lower carriage, the seat may be mounted upon the carriage itself.

15 Figs. 5 and 6 show an embodiment of my general invention relating to the raising and lowering mechanism, in which in lieu of the toothed pinions 17, 17, and racks 19, 19, of Figs. 1 to 4 a chain 30 is connected by one 20 end thereof with the transverse shaft 18^a upon the carriage 15^a, the said chain extending down from the said shaft and rearward under the wagon-body and its other end being connected with the latter at 30^a. 25 Fig. 6, or to some other convenient point of attachment, which might be rear cross-bar 9; a toothed pinion 17^a being fixed upon one or each end of said transverse shaft 18^a, and a rack 19^a being fixed upon one or each upper 30 side-bar 1. The said pinion 17^a is engaged by an actuating pinion 17^b on a transverse shaft 17^c. When the carriage is in its forward position, in which the rolls or disks 27, 27, on the transverse shaft 18^a are in contact with the front end of the wagon-body, the pinion 17^a is entirely at the front of the front end of the rack 19^a. In this position of the carriage, the chain 30 being unwound from the said transverse shaft 18^a, the wagon-body occupies its lowered position. If now 40 the transverse shaft 17^c be rotated so as to rotate the shaft 18^a, chain 30 will be wound upon the latter, and the front end of the wagon-body resting upon the chain will be 45 lifted. The rolls or disks 27, 27, will roll against the surface of the front end of the wagon-body as such end rises, holding pinion 17^a forward of the rack. When, however, the lower front corner of the wagon-body rises 50 above the rolls or disks 27, 27, the pull on the chain will cause the carriage to move rearward along the upper side-bars 1, 1, and pinion 17^a will enter into engagement with the rack. The engagement of the pinion 55 with the rack will operate to cause the carriage to continue its rearward movement, so as to carry the rolls or disks 27, 27, in under the wagon-body and tilt the latter upward. As this action proceeds the chain 30 will 60 wind upon shaft 18^a. By turning movement of the shaft 17^c in the other direction, causing shaft 18^a and pinion 17^a to turn in the reverse direction, the carriage will be caused to return toward the front end of the 65 wagon, thereby lowering the wagon-body.

In this turning movement the chain 30 will be paid out at a rate corresponding with the forward movement of the carriage. As the rolls or disks 27, 27, pass the lower front corner of the wagon-body they will cease to 70 support the latter, which will then be supported by the chain 30, and as a result of continued unwinding of the latter the wagon-body will be lowered to its normal position. The weight of the uplifted wagon-body may be relied upon to effect the return of the carriage to the front end of the wagon under control of the operator, such control determining the rate of descent of the 75 wagon-body into position again.

80 Figs. 7 and 8 show an embodiment of certain of the principles of the invention in which the fixed rack 19^a, and the pinion 17^a, are dispensed with, the tilting action being secured wholly by means of the chain 30, 85 and disks 27, 27, the construction otherwise being similar to that of Figs. 5 and 6. In the case of this embodiment the winding of the chain upon the shaft on the carriage will operate first to raise the wagon-body, 90 and then as soon as the front end of the latter has been lifted high enough to permit rolls 27, 27, to pass under the same the continued winding-on of the chain will operate to pull the carriage rearward under the 95 wagon-body, thereby completing the tilting of the latter.

100 The specific construction may be further varied in different respects without necessarily involving a departure from the spirit of my invention. For instance, I may make use of one or more racks at the front end, only, of the wagon-body, to coöperate with a corresponding number of pinions in lifting such end to admit the carriage, and may utilize one or more chains and winding means therefor to effect the rearward movement of the carriage. I may employ in the carriage a guide-pulley mounted on a shaft or other support forward of the winding shaft, to and around which pulley the chain passes on its way to the winding-shaft.

110 I claim as my invention:

1. In a wagon, in combination, a wagon-frame comprising long upper side-bars, short lower side-bars, and framework extending downward from the said upper side-bars and connecting with the lower side-bars, the front portions of the upper side-bars projecting forward from the said framework, and overhanging, with a space below the overhanging portions of the upper side-bars, and in advance of the front ends of the lower side-bars, an engine or motor occupying said space on a level with said framework, front wheels, also occupying said space, a wagon-body within said framework, and supports therefor connected with the lower side-bars.

2. In a wagon, in combination, a wagon-

4. In a wagon, in combination, a wagon-frame comprising long upper side-bars, short lower side-bars, and framework extending downward from the said upper side-bars and connecting with the lower side-bars, the front portions of the upper side-bars projecting forward from the framework and overhanging, with a space below the overhanging portions of the upper side-bars, and in advance of the front ends of the lower side-bars, an engine or motor occupying said space on a level with said framework, front wheels, also occupying said space, a wagon-body within said framework pivoted in connection with the frame and resting upon supports connected with the lower side-bars.

5. In a wagon, in combination, a wagon-frame comprising long upper side-bars, short lower side-bars, and framework connecting the rear portions of said upper side-bars with the lower side-bars, the front portions of the upper side-bars projecting forward from the framework and overhanging, with a space below the overhanging portions of the upper side-bars, and in advance of the front ends of the lower side-bars, an engine or motor occupying said space on a level with said framework, front wheels also occupying said space, and cross-bars extending from side to side between the lower side-bars, and a wagon-body between the upper side-bars, resting upon the said cross-bars, and swinging upon a pivotal mounting in connection with the frame.

6. In a wagon, in combination, a wagon-frame comprising upper side-bars, lower side-bars, bars connecting the upper side-bars with the lower ones, and cross-bars extending between the lower side-bars, a drop-axle on which the rear wheels are mounted and on the dropped portion of which, also, the lower side-bars rest, and a wagon-body between the upper side-bars, resting upon the cross-bars, and pivoted to the frame.

7. In a wagon, in combination, a wagon-frame comprising upper side-bars, lower side-bars, bars connecting the upper with the lower side-bars, and cross-bars extending between the lower side-bars, a drop-axle on which the rear wheels are mounted and on the dropped portion of which, also, the lower side-bars rest, and a wagon-body between the upper side-bars, resting upon the cross-bars, and pivoted to the frame.

8. In a wagon, in combination, a wagon-frame, a tilting wagon-body, a carriage or slide movably mounted in connection with said wagon-frame, and normally occupying a position in advance of said wagon-body and devices for partly raising the front end of the wagon-body to admit the said carriage or slide under the same or a part in connection therewith, and then causing rearward movement of the carriage or slide, thereby completing the tilting of the wagon-body.

9. In a wagon, in combination, a wagon-frame, a tilting wagon-body, a carriage or slide movably mounted in connection with said wagon-frame and normally occupying a position in advance of said wagon-body and devices for 70 tilting the wagon-body to dump, including a shaft on said carriage or slide, and continued rotation of the shaft producing rearward movement of the carriage or slide and thereby completing the tilting of the wagon-body. 80

10. In a wagon, in combination, channeled side-bars, a tilting wagon-body, a carriage or slide guided by the said channeled side-bars, and normally occupying a position in advance of said wagon-body and devices for 85 tilting the wagon-body to dump, including a shaft on said carriage or slide, and operative connections by which on rotation of said shaft the front end of the wagon body is partly raised to admit the carriage or slide under the same or a part in connection therewith, continued rotation of the shaft producing rearward movement of the carriage or slide and thereby completing the 90 tilting of the wagon-body. 95

11. In a wagon, in combination, a wagon-frame, a tilting wagon-body, a carriage or slide movably mounted in connection with said wagon-frame in advance of said wagon-body and having one or more rolls, and devices for partly raising the front end of the wagon-body to admit the said roll or rolls under the carriage body or a part in connection therewith, and then causing rearward movement of the carriage or slide and thereby completing the tilting of the wagon-body. 100

12. In a wagon, in combination, a wagon-body, a wagon-frame having the said body mounted therein with capacity to tilt for dumping, and also having side-bars which project at the front beyond the said body, a carriage or slide mounted on said side-bars, and normally occupying a position upon the forward projections, and devices for raising the front end of the wagon-body high enough to admit the carriage or slide under the same and then causing rearward movement of the carriage or slide and thereby completing the tilting of the wagon-body. 110

13. In a wagon, in combination, a wagon-body, a wagon-frame having the said body mounted therein with capacity to tilt for dumping a carriage or slide movably mounted in connection with said wagon-frame, and devices for tilting the wagon-body for dumping by first raising the front end thereof to admit the carriage or slide under the wagon-body or a part in connection therewith and then causing rearward movement of the carriage or slide to complete the 120 tilt. 130

ing, including a toothed wheel or wheels mounted on the carriage or slide and a corresponding rack or racks extending from front to rear of the wagon.

- 5 12. In a wagon, in combination, a wagon-body, a toothed rack extending down the front of said body and also lengthwise of the latter, a wagon-frame having the said body mounted therein with capacity to tilt for dumping, a carriage or slide movably mounted upon the wagon-frame and an actuating toothed wheel mounted thereon and engaging with said rack, whereby the rotation of said wheel first raises the front of the wagon-body to admit the carriage or slide under the same or a part in connection therewith and then moves the carriage or slide rearward and thereby completes the tilting of the wagon-body.
- 10 15. 13. In a wagon, in combination, a wagon-body, toothed racks extending down the

front of said body, and also lengthwise of the latter, a wagon-frame having the said body mounted therein with capacity to tilt for dumping, a carriage or slide movably mounted upon the wagon-frame, a shaft thereon provided with toothed wheels engaging with said racks, and one or more rolls on said shaft, whereby rotation of the shaft and toothed wheels first raises the front of the wagon body to admit the carriage or slide under the same or parts in connection therewith and then moves the carriage or slide rearward and thereby completes the tilting of the wagon-body.

In testimony whereof I affix my signature in presence of two witnesses.

PAUL HANNAGAN.
